ATTORNEY

UNITED STATES PATENT OFFICE

JEROME S. GWYNNE, OF CARSON, WASHINGTON

WIRE STRETCHER

Application filed February 26, 1929. Serial No. 342,925.

This invention relates to wire stretchers such as are used for stretching fence wire strands:

A primary object of the invention is to provide a stretcher of this character which is simple and cheap to manufacture, strong and reliable and which may be quickly applied to fence posts for stretching the wire to be attached thereto and removed when necessary to use it in connection with another wire or with the same wire to be connected to another post.

Another object of the invention is to so construct a device of this character that it may be held to the post by a single fastener and which has means for engaging the wire being stretched so as to prevent the pivoting of the stretcher on the post.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a front elevation of a portion of a fence post and a wire strand with this improved stretcher shown in position ready for use;

Fig. 2 is a longitudinal section thereof with parts broken out;

Fig. 3 is a transverse section taken on the line 3—3 of Fig. 2;

Fig. 4 is a similar view taken on the line 4—4 of Fig. 2; and

Fig. 5 is a perspective view of the bolt used for mounting the stretcher on a fence post.

In the embodiment illustrated a fence post P is shown of ordinary construction being of wood of any desired shape and into which is driven an L-shaped bolt 1 having the short end thereof flattened and sharpened to form a knife edge, and driven perpendicularly into the post. By driving the flattened end of this bolt perpendicularly into the grain of the

post turning of the bolt or holder in the post is prevented. This bolt 1 forms a support for mounting the wire stretcher 10 on the post P.

The wire stretcher 10 comprises a hollow cylindrical member 11 constructed of heavy metal preferably of one inch gas pipe four feet long the upper wall of which is slotted longitudinally as shown at 12 to provide for the sliding therein of a ratchet bar 13 the teeth 14 of which project through the slot 12 above the pipe 11. This sliding ratchet bar 13 has its inner edge slit transversely at intervals and portions thereof bent outwardly in opposite directions to form guiding arms 15 and 16 shown clearly in Fig. 4 which engage the walls of the pipe 11 and hold the ratchet teeth in operative position and prevent wobbling of the bar in the pipe.

Secured to the bottom of the pipe 11 is a reinforcement bar 17 composed of wood or any suitable material bolted or otherwise secured to the pipe and which is apertured transversely for the passage therethrough of the post attaching bolt 1.

At one end of the ratchet bar 13 is an upstanding clamp 18 for gripping and holding the wire 2 to be stretched. This clamp 18 as shown is composed of two jaws 19 and 20 which straddle the end of the ratchet bar 13 and are riveted or otherwise fixedly secured thereto. Intermediate their ends these jaws are bowed outwardly as shown at 21 to form a wire receiving space while the upper ends above said space are to be arranged in contact with each other and are apertured to receiving a clamping bolt 22 which has a head or upset portion 23 at one end and the other end threaded and provided with a nut 24 for tightening or loosening the jaws to clamp the wire therebetween.

A loop member 25 is designed to straddle the wire 2 between the post to which the stretcher is to be attached and the one to which it has previously been secured and which has the ends thereof bent laterally and

adapted to be inserted in the pipe 11 as shown clearly in Figs. 1 and 2 to hold it frictionally engaged with the pipe after it has been slipped over the wire to hold the stretcher 5 against up and down movement or sidewise movement. The loop member 25 also serves as a guide for wire 2, during the stretching operation.

A locking device for the ratchet bar 13 is shown at 26 and is preferably made in the form of a substantially L-shaped loop member, the loop portion of which is designed to engage the teeth 14 of the rack bar while the ends of said member straddle the ratchet 15 bar, the pipe and the reinforcement 17 and have their terminals bent and extended laterally and are pivotally connected with the reinforcement bar 17. This locking dog or pawl 26 when engaged with the teeth 14 of 20 the ratchet bar as shown clearly in Figs. 1 and 2 will hold the ratchet bar against pulling in the direction of the strain exerted by the wire 2 being stretched.

An operating lever 31 is pivotally connected 25 with the stretcher body preferably at one side of the aperture through which the bolt 1 extends. This lever 31 is shown bifurcated at its connected end and the furcations 28 and 29 thereof straddle the ratchet bar, the pipe 30 and the reinforcement bar and are preferably connected with the reinforcement bar by a pivot rod or shaft 30. A U-shaped pawl 32 has the legs thereof pivotally connected with the furcations 28 and 29 of the lever as is 35 shown clearly in Fig. 3. This pawl 32 straddles the rack bar 13 and the cross-bar formed by the connected ends thereof is designed for engagement with the teeth 14 whereby the bar with the wire 2 connected therewith will be 40 moved in the direction in which the wire 2 is to be stretched upon the forcible movement of the lever 27 towards the left. When it has been moved to its fullest extent the latch pawl 26 will drop down into engagement with 45 the teeth 14 and hold the rack bar when the lever 31 is being moved forward to take another grip on the bar for exerting a further pull on the wire 2.

It will thus be seen that with the wire 2 50 designed to be nailed or stapled to the post P the wire stretcher 10 is mounted on said post by the bar 17 being slipped on said bolt 1 up close against the post in which position the bar 55 and the wire clamped thereto will have just enough clearance to slide easily without wobbling since the draft is straight back on the wire 2 and the stretcher is kept in place without turning the post or bending the bolt.

When it is desired to change the stretcher 60 from one post to another or from one point on one post to another point thereon all that is necessary is to tap the stretcher or the bolt with a hammer to loosen the bolt and it can 65 be moved to another position and again driv-

en into the post in the manner above described.

Without further description it is thought that the features and advantages of the invention will be readily apparent to those skilled in the art, and it will, of course, be understood that changes in the form, proportion and minor details of construction may be resorted to, without departing from the spirit or the invention or its scope as claimed.

I claim:

1. A wire stretcher comprising a tubular body member adapted to be removably mounted on a fence post and having a tubular portion, said portion being longitudinally slotted from end to end, a ratchet bar mounted to slide in said slot and having laterally bent arms fitting within the tube and adapted to guide the ratchet bar and prevent wobbling of the same therein, an upstanding wire engaging clamp at one end of the ratchet bar, an operating lever fulcrumed on said body member and having a U-shaped pawl for moving the ratchet bar in one direction against the strain of a wire held by the aforesaid clamp, and a locking pawl carried by the body member on the opposite side of the fulcrum of the operating lever to engage a tooth of the ratchet bar and hold it in adjusted position.

2. A wire stretcher comprising a tubular body member adapted to be removably mounted on a fence post and having a tubular portion, said portion slotted longitudinally from end to end, a ratchet bar slidably mounted in said slot, the teeth projecting beyond said tube, said ratchet bar having laterally bent arms engaging the inner wall of the tube to act as guides and prevent wobbling of the ratchet bar, an upstanding wire engaging clamp projecting from one end of the ratchet bar, a wire guide loop frictionally held in the opposite end of the tube and adapted to straddle and guide the wire to be stretched, an operating lever fulcrumed on said body member having a pawl adapted to engage the teeth of the ratchet bar to move the same in one direction against the strain of the wire clamped thereon, and means for locking the ratchet bar in adjusted position.

3. A wire stretcher comprising a reinforcing bar adapted to be removably mounted on a fence post, a tubular body member rigidly secured to said reinforcing bar, said body member slotted longitudinally from end to end, a flat ratchet bar slidably mounted in said slot, a plurality of laterally bent arms extending from said ratchet bar and snugly fitting within said tubular body member, and adapted to provide guides for said bar and prevent wobbling thereof, an upstanding wire engaging clamp at one end of the ratchet bar, an operating lever fulcrumed on said reinforcing bar and having a U-shaped pawl adapted to move the ratchet bar in one di-

rection against the strain of a wire held by the aforesaid wire clamp, a locking bail pivotally secured on said reinforcing bar adapted to engage the teeth of the ratchet bar and hold it in adjusted position, and detachable means held in one end of the tubular body member adapted to act as a wire guide and a support for the end of the tubular body member.

10 Signed at Stevenson, in the county of Skamania and State of Washington, this 14th day of February, A. D. 1929.

JEROME S. GWYNNE.
